ANDREW EUGENE MICHAELSON, OF PORTLAND, OREGON, ASSIGNOR, BY MESNE ASSIGNMENTS, OF FORTY-NINE PER CENT TO HILDA ESCHENFELD, OF PORTLAND, OREGON.

GARAGE DOOR OPERATOR

Application filed July 18, 1928. Serial No. 293,521.

This invention relates to door operators for garages and the like.

A primary object of the invention is to provide mechanism of this character which is 5 a great labor saver being operable by a car driver without necessitating the leaving of the car and which may be easily installed and operated and which is so simple in construction that it may be manufactured and sold 10 at a price within the reach of every car owner.

Another object is to so construct such an apparatus that the doors may be conveniently and substantially locked in either open, closed or partly closed position in accordance with 15 the wishes of the operator.

Another object is to so construct and mount an apparatus of this character that it will be entirely concealed when viewed from the outside when the doors are open except 20 for an extension of the operating wheel.

Still another object is to so construct an apparatus of this character that oppositely wound pull ropes are so connected that a pull on one will actuate the doors with which 25 they are connected and simultaneously wind up the other rope ready to be pulled for actuating the doors in the opposite direction, said pull being alternately operable to unwind one rope and wind up the other and to simultaneously operate the doors according to the 30 wishes of the operator.

In carrying out these objects the invention is susceptible of a wide range of modification without departing from the spirit or sacrificing any of the advantages of the claimed 35 invention; there being shown in the drawings for illustrative purposes a preferred and practical form, in which:

Figure 1 represents a side elevation of a 40 garage equipped with this improved door operator with an automobile shown approaching the garage;

Fig. 2 is a detail perspective view of a portion of the housing containing the pull mechanism and which is here shown locked;

Fig. 3 is a rear elevation of the door operating mechanism with the garage within which it is mounted shown partially broken out and in section;

Fig. 4 is a bottom plan view of the mecha-

nism with the doors shown in closed position in full lines and in open position in dotted lines, with the walls of the garage in section;

Fig. 5 is a front elevation of the housing which is located at a point in the front of the garage and which contains the pull mechanism for operating the door opener with the front and rear walls of the housing shown removed, those illustrated being in section;

Fig. 6 is a vertical section taken on the line 6—6 of Fig. 5;

Fig. 7 is a detail vertical section taken on the line 7—7 of Fig. 5;

Fig. 8 is a horizontal section taken on the line 8—8 of Fig. 5;

Fig. 9 is a similar view taken on the line 9—9 of Fig. 5;

Fig. 10 is a detail perspective view of one of the castings constituting a part of the invention;

Fig. 11 is a detail perspective view of one of the locking dogs employed for locking the doors in adjusted position; and

Fig. 12 is a similar view of the other dog used for this purpose.

In the embodiment illustrated a garage 1 of ordinary construction is shown having the usual pitched roof 2 and double doors 3 and 4, which later are hinged to swing outwardly into open position as shown clearly in dotted lines in Fig. 4, and in connection with which the operating mechanism constituting this invention is shown.

An upright housing 5 is shown located at a point in advance of the front of the garage at 85 one side of the drive way and within which a portion of the door operating mechanism is located and which is protected against tampering by means of the hinged door 6 which normally is kept locked and the key in the possession of the car driver. A pipe 7 preferably of galvanized iron connects the upper end of the housing 5 with the upper portion of the front of the garage above the door frame, floor flanges 8 and 9 being located at 90 the opposite ends of the pipe 7 where it joins the housing 5 and the garage. Rotatably mounted in the housing 5 is a power pulley 10 preferably made in the form of a wooden wheel about eight inches in diameter more or

less which is provided at its opposite ends with heads 11 and 12 having ratchet teeth formed in the peripheries thereof. The teeth of one wheel extend in a direction opposite to those of the other. These heads or castings 11 and 12 are preferably made of metal about one-half inch thick and about nine inches in diameter and they are rigidly secured to the pulley by bolts or other suitable means. The pulley 10 is mounted on an axle journalled in the housing 5 in the form of a bolt 15 which extends through opposite faces of the housing as shown clearly in Fig. 9. Pull ropes 13 and 14 are wound around the pulley 10 in opposite directions and secured to the pulley at one end while at their other end they are equipped with hand grips 13a and 14a respectively. These pull ropes 13 and 14 are of a length to enable them to be unwound sufficiently from the pulley for operating the doors in the manner presently to be described without disturbing the anchorage of the ropes on the pulley, there being one more turn of the rope around the pulley than is necessary to complete the operation of the doors.

By pulling on the rope 14 to unwind it for a length from twenty to twenty-six inches it operates to turn the pulley backwards sufficiently to close the garage doors and during this unwinding and turning backward of the pulley the pull rope 13 is wound up on the pulley. If the rope 13 is drawn out from twenty to twenty-six inches it unwinds, pulling the pulley 10 forwardly to open the doors and automatically winds the rope 14 back into position.

Substantially U-shaped pawls 16 and 17 are pivotally mounted between the side walls 40 of the housing 5 and in part comprise a locking device for the doors 3 and 4. When the pull ropes 13 and 14 are both at rest the pawls 16 and 17 through their teeth 16a and 17a engage the ratches of the heads 11 and 12 thereby preventing the pulley 10 from moving in either direction. The pawl 16 has its tooth 16a at the free end of one of its arms and pawl 17 has its tooth 17a on its cross bar. It will be seen from an inspection of Fig. 5 that when in this position the pawls rest on and overlie the ropes 13 and 14. When a pull is exerted on rope 13 pawl 17 is disengaged from the teeth of the ratchet head 11 and it remains disengaged so long as there is a tension on the rope 13. During the process of pulling rope 13 and disengaging pawl 17, pawl 16 is engaged with the ratchet teeth of head 12 thereby preventing it from moving in a direction opposite to that of head 11. By pulling rope 14 the effect is the same as when rope 13 is pulled except that it is reversed. By releasing the tension of either or both the ropes 13 or 14 the pulley 10 locks instantly and remains in set position. This arrangement provides a convenient, practical and

substantial lock for the doors when open or closed wholly or in part.

A flexible wire cable 20 is trained around the power pulley 10 and connected with the main operating wheel 30 which latter will be presently more fully described.

An extension block 25 is located on the outside of the top of the housing box 5 as shown clearly in Fig. 5 and is cut with a recess on its inner face to receive a casting 26 which supports pulleys 21 and 22 and also guide pulleys 23 and 24 which latter are arranged in planes at right angles to the former. This casting 26 is secured to the extension block by a plurality of bolts 27 which pass through the front facing or flange 28 and through the block 25 as is shown clearly in Figs. 5 and 6. The extension block 25 is provided with a pipe receiving or communicating opening 29 around which the floor flange 8 is arranged and by means of which the pipe 7 is secured to the block as is shown clearly in Fig. 5. This construction insures the proper alignment of the pipe opening with the pulleys and prevents any possibility of them getting out of register.

The inside opener assemblage is shown in Figs. 3 and 4 and comprises what we will term the main opener wheel 30 and the auxiliary opener wheel 40. These wheels 30 and 40 are rotatably mounted on a hard wood beam 50 and on which are also mounted guide pulleys 51 and 52 around which is trained the cable 20 to place it in alignment with the pipe 7. This beam 50 is shown suspended by hangers or irons 53 depending from the roof 2 of the garage said beam being braced at its ends by irons 54 secured to the side walls of the garage as is shown clearly in Fig. 3, it of course being understood that the beam may be braced at any other point found necessary to hold it rigid and in permanent position. It will be observed that this beam and the parts supported thereby are located some distance above the door casing for which there are two reasons, the first being that the whole assemblage is hidden from view from outside when the doors are open and second, it permits boring the hole leading to the pipe 7 sufficiently high above the top of the door to permit the doors to swing under said pipe if so desired. It will readily be seen that when the doors are open the only things visible to the outside are the opener wheel extensions 35 and 45 which swing under the top casing and just outside of it and which will be hereinafter more fully described.

The two pulleys 51 and 52 are so mounted at the end of beam 50 that they may be conveniently moved backward or forward to more easily place them in direct alignment with the mouth of the pipe 7 before anchoring the pulley. You can see in this mounting the cable 20 will be prevented from rubbing against any metal and by so doing will ex-

tend the life of the entire apparatus indefinitely.

The cable 20 is trained around the main opener wheel 30 and is secured thereto by the 5 tightener 31. This cable then passes around pulleys 51 and 52 through pipe 7 over the pulleys 21 and 22 in the housing 5 and between the guide pulleys 23 and 24 thereof and around the power pulley 10. The cable 10 is wound three times around the power pulley 10. It is understood, of course, that cable 20 is attached at both ends to the wheel 30, pulleys 51 and 52 may be moved backward or forward until in perfect and direct alignment with the opening in pipe 7 and then they are made fast. After this has been done the catch 32 at the end of the bolt 31 is turned until all slack is taken out of the cable 20. This cable 20 being also made fast to the 20 power pulley 10 there is no possible way by which either outside or inside mechanism can get out of adjustment since the reciprocating motion between them will always remain the same.

25 A cable 60 the same size as the cable 20 is secured at 33 to the main opener wheel 30 and is then passed around wheel 30 to cable tightener 34 of the wheel 40 and anchored. This cable 60 is passed around the wheel 40 back to the point of beginning on wheel 30 where it is secured. This cable is provided with tighteners in both the wheels 30 and 40 and is attached to these wheels before shipping. The wheel 30 is termed the main opener wheel because it receives the reciprocatory motion from the power pulley 10 and drives the auxiliary wheel 40 by means of the cable 60 as shown in Fig. 4.

The two wheels 30 and 40 are provided 40 with radially projecting extensions 35 and 45 respectively and which are connected by links 36 and 46 with the doors 3 and 4, said links being pivotally connected at one end to the doors and at the other end to the extension of their respective wheels. It will thus be seen that a pull on the cable 20 in one direction will simultaneously turn the wheels 30 and 40 and through the extensions carried thereby and the links 36 and 46 operate 45 to open the garage doors 3 and 4 into the dotted line position shown in Fig. 4 and when turned in the opposite direction incident to a pull on the other end of cable 20 these wheels will be swung inwardly and the doors 50 closed.

In Fig. 1 both of the garage doors are shown in open position and securely locked in that position by means of the dogs 16 and 17. To unlock these doors the door 6 of the housing 5 is first unlocked which exposes the two pull ropes 13 and 14. A pull exerted on one of these ropes automatically releases the locking device and at the same time draws both garage doors into closed position and at the 55 instant the tension of the pull rope is released

the pawls automatically lock leaving the doors in a closed locked position. To open the doors a pull on the opposite rope is given, the mere tension of which releases the locking device and permits the doors to open. When the doors are completely open the releasing of the tension on the rope pulled releases the pawls and they instantly drop into engagement with the teeth of their respective ratchet plates and lock the doors in their open position. When the doors 3 and 4 are closed and locked and the small door 6 of the housing locked the entire apparatus will be secured against unauthorized opening.

While this operating device is disclosed as used in connection with garage doors obviously it may be used on gates and other doors.

Without further description it is thought that the features and advantages of the invention will be readily apparent to those skilled in the art, and it will, of course, be understood that changes in the form, proportion and minor details of construction may be resorted to, without departing from the spirit of the invention or its scope as claimed.

I claim:

1. An operating mechanism for doors and the like comprising a power pulley, means for locking said pulley to hold the door in connection with which it is used in either open or closed or partially opened or closed position, and a cable wound on said pulley and operable by pull exerted thereon to simultaneously release said locking means and actuate the pulley to operate the door.

2. A door operating mechanism comprising a supporting structure, a power pulley mounted to rotate in said structure, means for locking said pulley in adjusted position, cables wound on said pulley and operable by a pull to operate said pulley in opposite directions and also to release said locking means, an oscillating member connected with the door to be operated, and a connection between said oscillating member and said pulley whereby the turning of the pulley will actuate said member to open or close the door.

3. An operating mechanism for doors and the like comprising a power pulley, a connection between said pulley and the door to be operated whereby the turning of the pulley will operate the door, pull ropes wound around the power pulley in opposite directions and secured at one end thereto and means for locking said pulley in adjusted position said means being releasable by pull on one of said ropes.

4. An operating mechanism for doors and the like comprising a power pulley, having ratchet plates at the opposite ends thereof, the teeth of one plate extending in a direction opposite those of the other, pawls for engaging said teeth to lock the pulley in adjusted position, pull ropes wound on said

5 pulley in opposite directions and anchored at one end thereto, one of said ropes being engaged with one pawl and the other with the other whereby a pull on either will release its cooperating pawl, and a connection between said pulley and the door to be operated controlled by the turning of the pulley.

6 5. An operating mechanism for doors and
10 the like comprising a power pulley, a cable secured to and wound on said pulley, a connection between said pulley and the door to be operated, means for locking said pulley, said locking means being released and said
15 pulley actuated by the unwinding of said cable to open or close the door in connection with which the mechanism is used.

6 6. An operating mechanism for doors and the like comprising a main and an auxiliary
20 opener wheel spaced from each other and mounted to rotate, a cable trained around said wheels and attached to both of them, said wheels having radial extensions with links connecting said extensions to the doors to be
25 operated, and an operating cable trained around said main opener wheel and fixed thereto whereby a pull exerted on said cable will operate to turn both of said wheels to open or close the doors.

30 7. An operating mechanism for doors and the like comprising a power pulley, cables secured to and wound on said pulley in opposite directions, a connection between said pulley and the door to be operated, ratchet
35 plates at the ends of said pulley, the teeth of one plate extending in one direction and those of the other in the opposite direction, U-shaped pawls spanning said pulleys and pivotally mounted at their ends, one of said
40 pawls having a tooth on its cross bar to engage one of said ratchet plates, and the other having a tooth on one end for engaging the other ratchet plate, the cross bars of said pawls overlying and resting on said cables
45 whereby a pull on one of said cables will release its cooperating pawl and simultaneously turn the pulley to actuate the door with which it is connected.

ANDREW EUGENE MICHAELSON.
